DESIGN FOR A CHECK WRITING MACHINE

Henry Dreyfuss, New York, and Walter B. Payne,
Rochester, N. Y., assignors to The Todd Com-
pany, Inc., Rochester, N. Y., a corporation of
New York

Application December 29, 1933, Serial No. 50,260

Term of patent 14 years

To all whom it may concern:

Be it known that we, HENRY DREYFUSS, a citizen of the United States, residing at the city of New York, in the county of New York and State of New York, and WALTER B. PAYNE, a citizen of the United States, residing at the city of Rochester, in the county of Monroe and State of New York, have invented a new, original, and ornamental Design for a Check Writing Machine, of which the following is a specification, reference being had to the accompanying drawing, forming a part hereof.

Fig. 1 of the drawing is a perspective view of a check writing machine embodying our design looking at it obliquely from one side, and

Fig. 2 is a similar view of the same looking at it obliquely from the opposite side.

We claim:

The ornamental design for a check writing machine substantially as shown.

HENRY DREYFUSS.
WALTER B. PAYNE.
